J. Edward Thebaud.

UNITED STATES PATENT OFFICE.

WILLIAM F. ULLMAN AND WILLIAM C. HILLSINGER, OF SYRACUSE, NEW YORK.

ANGLE-COCK.

1,390,314.

Specification of Letters Patent. Patented Sept. 13, 1921.

Application filed February 17, 1920. Serial No. 359,339.

To all whom it may concern:

Be it known that we, WILLIAM F. ULLMAN and WILLIAM C. HILLSINGER, citizens of the United States, residing at Syracuse, in the county of Onondaga and State of New York, have invented new and useful Improvements in Angle-Cocks; and we do hereby declare the following to be a full, clear, and exact description of the same, such as will enable others skilled in the art to which it appertains to make and use the same; reference being had to the accompanying drawings, and to figures of reference marked thereon, which form part of this specification.

Like figures of reference refer to like parts.

This invention relates to angle cocks.

One object of this invention is to provide an angle cock of such a construction as will, upon a slight turning of the handle from a shut-off position, cause a communication between the hose side of the cock and the atmosphere, to bring about a reduction of pressure in the train line on the car, directly connected with the cock, which reduction of pressure will cause the setting of the air brakes in the well known manner.

A further object of this invention is to provide an angle cock of such a construction as will permit a gradual increase in leakage of air from the interior of the cock, as the handle is turned.

With these and other objects our invention consists in certain construction which is illustrated in the drawings, is hereinafter described, and what we claim is set forth.

In the drawings,

Figure 1 is a side elevation of an ordinary angle cock, showing our improvement embodied therein.

Fig. 2 is a top plan section of the angle cock shown in Fig. 1, taken on the line X—X of Fig. 1.

Fig. 3 is a longitudinal medial vertical section of the angle cock casing, shown in the other two figures.

Fig. 4 is a section taken on the line Y—Y of Fig. 3.

Fig. 5 is an elevation of the hollow plug.

Fig. 6 is a diagrammatic section of the plug and bushing of the angle cock casing, taken on the line A of Fig. 1, showing a cer-

tain position of the plug relative to the ports in the casing.

Fig. 7 is a diagrammatic section of the 55 plug and bushing of the angle cock casing taken on the line B of Fig. 1, showing another position of the plug relative to the ports in the casing.

Fig. 8 is a diagrammatic section of the 60 plug and bushing of the angle cock casing taken on the line C, showing the position of the plug relative to the ports in the casing, with one of the three ports entirely closed off, and full communication established 65 through the side port in the casing.

In the figures, is shown the angle cock casing 1, with a pipe receiving end 2, and a hose receiving end 3, connected by the channel 4, which is restricted at the vertical ports 5 and 6 through the bushing 7, which is fixed within the casing 1. A plug 8 fits in the ordinary way within the bushing 7 and is held in by the nut 8^a. The plug 8 has a square extension 9, upon which is a projection 10, fitting into the member 11, which is pivoted at 12, to the handle wrench 13 in the usual way, with the projection 10 positioned toward the hose end of the angle cock. The member 11, is pinned to the extension 9. Integral with and depending from the upper part of the member 11, is a lip stop 11^a. Passing through one of the side walls of the casing 1, and the bushing 7, is a series of four holes, 14, 15, 16 and 17, which open into 85 a pocket 18 on the outside of the casing 1, which pocket is open below and may, for purposes of construction, be made separable from the casing 1. These holes vary in size, the smallest being at the top, and the line of 90 their centers being angular and tilted at the top toward the hose end of the angle cock. The plug 8 has two vertical ports 19 and 20 diametrically opposed to one another, which register with the respective ports 5 and 6, 95 when the angle cock is full open for communication through the chamber 8^b. Through one side of the plug 8 is the port 21, having an angular extension 21^a, which, when the angle cock is wide open, inclines toward the 100 pipe or square end of the angle cock casing.

In operation, assuming that the valve is in the full open position as shown in Figs. 1 and 2, having the ports 5 and 6 of the cas-

ing bushing 7 register with the ports 19 and 20 of the plug 8, establishing full communication between connecting parts of the train line through this angle cock, having the atmosphere ports 14, 15, 16 and 17 closed off by a blank portion of the plug 8. Assume now, that the handle 13 is partially turned counter-clockwise, after being raised to release the interference of the lug 1^a on the 10 casing 1, with the lug 13^a on the handle 13, so that the relative position of the ports is as shown in Fig. 6, where the port 19 of the plug 8 is just beginning to eclipse the small hole 17, permitting a leak to atmosphere, 15 and the port 21 is opening onto the port 5, while at the same time the port 20 is leaving the port 6. Such a partial turn of the angle 20 cock handle 13 will throw both connections of the train line, communicating with the casing 1, into communication with the atmosphere through the hole 17, and if left so, will reduce the pressure of the train line, 25 at this point sufficiently to set the brakes, providing the pump supply, which maintains the air pressure within the pipe, is not sufficient to overcome the reduction of 30 pressure caused by such a leak. A further turning of the handle 13, in a counter-clockwise direction, will bring the hole 15 in open registration with the port 19, and the port 6 will be shut-off entirely on account of the port 20 passing beyond registration with the port 6. The port 21 will 35 open more in communication with the port 5, and the hose side of the angle cock will lose its pressure through the holes 15 and 17, and the brakes will be set on the car directly connected with the hose side of the angle cock. The position shown in Fig. 8 represents nearly a one-fourth turn of the handle 40 13, from the full open position, establishing full communication between the port 19 and all of the holes 14, 15, 16 and 17. The angular portion 21^a in the upper part of the slot 45 21, continues the communication between the port 5 and the chamber 8^b, after the lower part of the slot 21 has passed out of registration with the port 5, should the handle 13 be turned sufficiently for such a gradation of air flow from the hose side of the 50 angle cock to the chamber 8^b and thence to atmosphere through the holes 14, 15, 16 and 17.

By having the holes 14, 15, 16 and 17, reduced in size from bottom to top and having the line thereof turned forward, the communication made with the atmosphere, through the side of the valve is graduated. At the same time by having the portion 21^a of the 60 slot 21, of the plug 8, inclined to the rear, a gradation is effected at the upper end of the slot 21, as the same eclipses the port 5 on the hose side of the angle cock, co-incident with the partial opening of the port 19 onto 65 the smaller holes in the upper part of the

angle cock casing, communicating with the atmosphere.

It will be observed that such a construction is cheaply made and effects a practical gradation in ways of effecting a reduction 70 in the train line pressure, when the angle cock handle 13 is partially turned through accident or otherwise, and if through accident, then the brakes will automatically become set on the train or at least one part 75 thereof, giving the engineer definite warning as a signal that something has gone wrong, giving him the opportunity to fully stop his train for investigation, to right the difficulty in the system, before proceeding, 80 and thus avoid such accidents as are so commonly due to the accidental turning of the angle cock handle.

Having described our invention, we 85 claim—

1. In an angle cock for train lines, including the usual casing and handle, a plug having the usual diametrically opposed ports therethrough, connecting with a central chamber, there being a vertically positioned 90 angular slot through the wall of said plug, having its upper end inclined away from the hose side of said angle cock, when the valve is in full open position, and atmospheric ports passing through the opposite side of 95 said casing to that of the inclined slot of said plug, said atmospheric ports having direct connection through the wall of said angle cock with the atmosphere, whereby, upon the turning of said plug, said angular 100 slot opens communication between the hose side of the regular ports of said angle cock casing, co-incident with the opening of the other of the regular ports in said plug with said atmospheric port, whereby the angular 105 formation of said slot affords a means of gradation of the flow of air from said hose side of said regular ports, through said plug to the atmosphere.

2. In an angle cock for train lines, including the usual casing and handle, a plug having the usual diametrically opposed ports therethrough, connecting with the central chamber, a vertically positioned slot in the wall of said plug on one side of said casing, and a plurality of atmospheric ports passing through the side of said casing opposite said slot in said plug, the line of the centers of said ports being inclined in the same direction to that given said handle when opening said valve, whereby, upon the turning of said handle said ports come into communication with one of said usual ports in said plug, one by one upon the turning of said handle toward shutting off said valve.

3. In an angle cock for train lines, including the usual casing and handle, a plug having the usual diametrically opposed ports therethrough connecting with a central chamber, there being a vertically positioned 130

angular slot in the wall of said plug, inclined away from the hose side of said angle cock, when the valve is in full open position, and atmospheric ports passing through the 5 side of the said casing opposite to said inclined slot in said plug, said atmospheric ports consisting in a plurality of holes arranged vertically and having the line of the centers of said holes inclined in the opening direction of said angle cock and registerable with the hose side of one of said opposed ports in said plug, on the turning of said handle.

WILLIAM F. ULLMAN.

WILLIAM C. HILLSINGER.
